UNITED STATES PATENT OFFICE

2,423,495

WINDOW SASH RETAINING DEVICE

Stanley Galuska, Chicago, Ill.

Application October 22, 1945, Serial No. 623,675

2 Claims. (Cl. 292—75)

1

The present invention relates to window sash retaining devices, and has for its main object the provision of means for frictionally engaging window sash within a window frame for maintaining the same in a raised position within the frame.

A still further object of the present invention is the provision of a pair of wheels upon a window sash, and which may be maintained under tensioning pressure against the window frame for holding the sash in a raised adjusted position, and without employing usual weights and cords.

With the above general objects in view and others that will appear as the invention is better understood, the same consists in the novel construction, combination and arrangement of parts hereinafter more fully described, illustrated in the accompanying drawing and pointed out in the appended claims.

In the drawing forming a part of this application and in which like designating characters refer to corresponding parts throughout the several views;

Fig. 1 is a face elevational view of the window sash showing the relative position therewith of the retaining means constituting the present invention;

Fig. 2 is an enlarged longitudinal cross-sectional view through a corner of a window sash, with a side elevational view of the retaining device in its operative position with respect to a window frame;

Fig. 3 is a top elevational view of the window sash, with a corresponding view of the window sash retaining device, partly in section; and

Fig. 4 is a cross-sectional view on line 4—4 of Fig. 3.

Referring in detail to the present drawing there is shown therein window sash 10, with a pair of retaining devices, generally indicated by 11 in Fig. 1, one positioned at each upper corner of the window sash. The window frame within which window sash 10 is intended for positioning and with which said retaining devices 11 are intended to cooperate is indicated in Fig. 2 by 12.

Each upper corner of window sash 10 is provided with an L-shaped recess 13 for positioning therewithin L-shaped plate 14, the horizontal portion of said recess 13, made in the horizontal, upper sash bar of the window sash, is deeper than the vertical portion of said recess made in the adjacent vertical sash bar, for the purpose of accommodating therewithin the mechanism of the retaining device hereinafter described. Said L-shaped plate 14 is maintained in position

2

upon the sash by means of a plurality of screws 15.

Inserted upon the horizontal portion of said L-shaped plate 14 is housing 16, which is of substantially square formation on transverse cross-section and open at both of its ends.

The bottom of said housing 16 is below the horizontal portion of said L-shaped plate 14 and is accommodated within groove 17 made at the 10 end of the upper, vertical sash bar, and which groove communicates with said recess 13.

At some distance from the corner of said L-shaped plate 14 angle plate 18 is affixed to said L-shaped plate 14 by means of rivet 19. The 15 vertical portion of said angle plate 18 enters the inner end of housing 16, and is accommodated therein, as is clearly seen in Fig. 3.

The invention further includes cradle 20, including top wall 21 and a pair of side walls 22.

20 Journaled upon pins 23 carried by said side walls 22 and outwardly thereof, is a plurality of anti-friction wheels 24, which ride upon the upper face of the horizontal portion of said L-shaped plate 14, and the lower face of the upper wall of said 25 housing 16, for guiding said cradle 20 in its sliding movement within said housing 16.

At the outer end of said cradle 20 the upper wall 21 thereof is severed from side walls 22 and bent downwardly to define vertical transverse 30 wall 25. The outer ends of said side walls 22 constitute a pair of resultant rails 26, which extend beyond the outer end of housing 16, and which have wheel 27 journaled therein. The journaling means for wheel 27 includes axle 28 and nut 29 35 engaging said axle 28. Said wheel 27 may be made of metal having its periphery rubberized for frictionally engaging and contacting with window frame 12 as is seen in Fig. 2.

Inserted through said transverse wall 25 is rod 40 30 having head 31 which bears against the outer face of said transverse wall 25. The opposite end of said rod 30 extends through the vertical portion of said angle plate 18, and the outer reduced threaded end of said rod 30 carries nut 32 which 45 constitutes a means for limiting outward shifting movement of said rod 30.

Encompassing said rod 30 and interposed between said transverse wall 25 and the vertical portion of said angle plate 18 is coil spring 33, which 50 normally urges said cradle 20 away from said angle plate 18.

When window sash 10 is within window frame 12 wheel 27 contacts with said window frame 12 and is urged into a strong contact therewith by spring 33, which, bearing against the vertical por-

tion of angle plate 18, exerts a strong pressure upon transverse wall 25 for urging the same outwardly. Nut 32 does not come in contact with the outer face of the vertical portion of angle plate 18, and limits the shifting movement of rod 30 only when window sash 10 is removed from within frame 12, as is seen in Fig. 3. From the hereinabove description it will be seen that cradle 20 and wheel 27, due to the action of spring 33 are under a resilient, yielding tension, permitting wheel 27 to ride over any rough surfaces of frame 12 without jarring of the window sash in its vertical sliding movement within frame 12.

As is seen in Fig. 2 the mechanism of the retaining device, enclosed within housing 16 is countersunk within the horizontal portion of recess 13, thereby presenting a neat appearance for window sash 10 with no mechanism visible or projecting outwardly therefrom.

From the hereinabove description it will be apparent that a pair of window sash retaining devices 11, as is shown in Fig. 1, exerting a strong pressure in opposite directions and against window frame 12 will maintain window sash 10 in its raised adjusted position with said frame.

While there is described herein a preferred embodiment of the present invention, it is nevertheless to be understood that minor changes may be made therein without departing from the spirit and scope of the invention as claimed.

What I claim as new is:

1. A device for retaining a window sash within a frame comprising a cradle including a pair of spaced side walls and a top wall, said top wall adjacent one end of said cradle being severed from said side walls and bent angularly with relation to said top wall for effecting a transverse wall, a stationary plate, said transverse wall being in a parallel spaced relation with said plate, the

resultant ends of said side walls constituting a pair of spaced rails, a frame engaging member carried by said rails, a rod in engagement with said transverse wall and passing through said plate, and a coil spring encompassing said rod and interposed between said plate and said transverse wall, said coil spring exerting pressure upon said transverse wall for urging said rails away from said plate.

2. A device for retaining a window sash within a frame comprising a plate, a housing mounted upon said plate, said housing having open ends, a cradle positioned within said housing for a longitudinal shifting movement therein, a pair of rails integrally formed with said cradle and extending through the outer open end of said housing, anti-friction wheels carried by said cradle and contacting said plate and said housing for facilitating longitudinal sliding movement of said cradle, a plate rigidly affixed to said first named plate, said second named plate entering the opposite end of said housing, a rod in engagement with said cradle, a coil spring interposed between said cradle and said second named plate for urging said cradle away from said second named plate, and a frame engaging member carried by said rails, said spring urging said rails away from said second named plate.
